CLAIM

The ornamental design for a combined toilet trip lever and escutcheon, as shown and described.

DESCRIPTION

FIG. 1 is a perspective view of a combined toilet trip lever and escutcheon showing my new design;

FIG. 2 is a top plan view thereof;

FIG. 3 is a right side elevational view thereof;

FIG. 4 is a front elevational view thereof; and

FIG. 5 is a left side elevational view thereof.

The fragmentary broken line representation of a toilet tank in FIG. 1 is for purposes of illustration only.
